UNITED STATES PATENT OFFICE.

ADOLPH KAPLAN AND JOHN SEREDIUK, OF WINNIPEG, MANITOBA, CANADA.

FILE-HANDLE.

1,372,029.

Specification of Letters Patent. Patented Mar. 22, 1921.

Application filed May 20, 1920. Serial No. 382,943.

To all whom it may concern:

Be it known that we, (1) ADOLPH KAPLAN and (2) JOHN SEREDIUK, (1) a citizen of the Dominion of Canada and (2) a citizen 5 of Ukraine, residing at Winnipeg, in the Province of Manitoba and Dominion of Canada, have invented certain new and useful Improvements in File-Handles, of which the following is a specification.

10 The primary object of the present invention resides in the provision of a handle or support for carrying a removable file blade so that files having different gage teeth may be mounted upon the handle and rigidly 15 secured thereto when in operation.

20 A further object of the invention is to provide a removable file for a file supporting handle in which the cutting surface of the file is provided with a plurality of 25 apertures to facilitate the disposal of filings when the file is in use.

25 With the above and other objects in view, the present invention consists in the novel form, combination and arrangement of parts 30 hereinafter more fully described in connection with the accompanying drawing, wherein like reference characters indicate similar parts throughout the several views.

35 In the drawing, Figure 1 is a side elevational view of a file constructed in accordance with the present invention,

Fig. 2 is an edge view of the same,

35 Fig. 3 is a longitudinal sectional view showing the hinged clamping arms for the file blades,

40 Fig. 4 is a cross sectional view taken on line IV-IV of Fig. 1 showing the connection between the outer end of the file blade and the supporting frame,

45 Fig. 5 is a cross sectional view taken on line V-V of Fig. 1 showing the file blade engaging the shank of the handle, and

Fig. 6 is a cross sectional view taken on 45 line VI-VI of Fig. 1.

Referring more in detail to the accompanying drawing, there is illustrated a file supporting handle comprising a handle portion 7 carrying a flat shank 8 with opposite ribs 9 while the outer end thereof is provided with a head 10 carrying opposite dove-tail-shaped lugs 11 upon the opposite faces thereof for purposes presently to appear.

55 A novel type of file blade best illustrated in Figs. 1 and 3 is employed and includes

a blade portion 12 with portions of the surface thereof provided with a series of openings 13 through which filings may pass during the operation of the file. The file 60 blades 12 are each provided with an opening 14 adjacent its outer end and into which the lug 11 is received.

65 Retaining means for the inner ends of the file blades 12 is associated with the handle portion 7 and comprises a rod 15 that slidably projects into the cut-away portion 16 of the handle 7, while side strips 17 are secured to opposite faces of the handle 7, outwardly of the central slot 16 by 70 the bolts 18. An arm 19 is hinged to each side of the rod 15 at its inner end as at 75 while the inner faces of the outer arms 19 are provided with dove-tail-shaped lugs 21 that are adapted to be received in openings 75 22 formed in the inner ends of the file blades 12. The inner end of the rod 15 is provided with a threaded pin 23 to receive the thumb nut 24 while the washer 25 separates the nut 24 from the inner end 80 of the guard strips 17 and handle 7.

85 In positioning the file blades 12 upon the handle 7, the thumb nut 24 is released from engagement with the handle and the file blades positioned to cause the lugs 11 to enter the openings 14 in the outer ends thereof. The hinged arms 19 are then 90 swung upon their pivots 20 to cause the lug projections 21 to be received in the file openings 22 in the inner ends thereof, and by tightening the thumb screw 24 the rod 15 carrying said arms 19 will be moved inwardly relative to the handle 7 to cause the dove-tail-shaped lugs 11 and 21 to be prevented from movement relative to the file 95 blades 12, thereby rigidly mounting the blades 12 upon the handle 7. The type of file blade employed may be changed and during operation of the device the file is supported upon the side ribs 9 of the handle 100 shank 8.

105 While there is herein shown and described the preferred embodiment of the invention, it is nevertheless to be understood that minor changes may be made in the novel form, combination and arrangement of parts without departing from the spirit and scope of the invention as herein-after claimed.

What is claimed as new is:

110 1. A file support comprising a handle, a shank carried by the handle, a rod movable

relative to said handle, file blades connected at their outer ends to the handle shank, means connecting the inner ends of the file blades to said rod and means for holding 5 said rod rigid relative to said handle to prevent movement of the file blades relative to the shank.

2. A file support comprising a handle, a shank carried by the handle, a rod movable 10 relative to said handle, file blades connected at their outer ends to the handle shank, means connecting the inner ends of the file blades to said rod, means for holding said rod rigid relative to said handle to prevent 15 movement of the file blades relative to the shank, and ribs carried by the opposite sides of said shank for engaging the file blades intermediate their ends to rigidly support the same.

20 3. A file holder of the type described comprising a handle, a shank carried thereby, file blades connected at their outer ends to

the outer end of the shank, a rod slidably mounted relative to said handle, arms hinged to said rod and adapted to engage 25 the inner ends of the file blades and means associated with said rod and handle for holding the file blades rigidly mounted.

4. A file holder of the type described comprising a handle, a shank carried thereby, 30 file blades connected at their outer ends to the outer end of the shank, a rod slidably mounted relative to said handle, arms hinged to said rod and adapted to engage the inner ends of the file blades, a threaded 35 pin carried by said rod and a thumb nut upon said threaded pin adapted to engage the handle to hold the file blades rigidly positioned on the handle.

In testimony whereof we affix our signatures.

ADOLPH KAPLAN.
JOHN SEREDIUK.
